(57) **CLAIM**

The ornamental design for undergarment as shown and described.

DESCRIPTION

FIG. 1 is a front perspective view of a first embodiment of the undergarment;

FIG. 2 is a front view of the first embodiment of the undergarment;

FIG. 3 is a rear view of the first embodiment of the undergarment;

FIG. 4 is a front perspective view of the first embodiment of the undergarment with the crotch portion detached from the undergarment;

FIG. 5 is a front view of the first embodiment of the crotch portion;

FIG. 6 is a rear view of the first embodiment of the crotch portion;

FIG. 7 is a left side view of the first embodiment of the crotch portion;

FIG. 8 is a right side view of the first embodiment of the crotch portion;

FIG. 9 is a top view of the first embodiment of the crotch portion;

FIG. 10 is a bottom view of the first embodiment of the crotch portion;

FIG. 11 is a front perspective view of a second embodiment of the undergarment;

FIG. 12 is a front view of the second embodiment of the undergarment;

FIG. 13 is a rear view of the second embodiment of the undergarment;

FIG. 14 is a front perspective view of the second embodiment of the undergarment with the crotch portion detached from the undergarment;

FIG. 15 is a front view of the second embodiment of the crotch portion;

FIG. 16 is a rear view of the second embodiment of the crotch portion;

FIG. 17 is a left side view of the second embodiment of the crotch portion;

FIG. 18 is a right side view of the second embodiment of the crotch portion;

(Continued)

FIG. 19 is a top view of the second embodiment of the crotch portion; and,

FIG. 20 is a bottom view of the second embodiment of the crotch portion.

Broken lines appearing in the drawings depict portions of the undergarment that form no part of the claimed design.
